UNITED STATES PATENT OFFICE.

WILLIAM N. VANCIL, OF CANYON CITY, OREGON, ASSIGNOR OF ONE-THIRD TO A. D. LEEDY, OF CANYON CITY, OREGON,

SAGE-BRUSH GRUBBER.

1,331,731.

Specification of Letters Patent. Patented Feb. 24, 1920.

Application filed September 12, 1919. Serial No. 323,357.

To all whom it may concern:

Be it known that I, WILLIAM N. VANCIL, a citizen of the United States, residing at Canyon City, in the county of Grant and State of Oregon, have invented certain new and useful Improvements in Sage-Brush Grubbers, of which the following is a specification.

This invention relates to sage brush grubbing devices and it has for its object to provide a sage brush grubber comprising but a few simple and inexpensive parts and constructed in such manner that it will closely hug the ground and grub up the sage brush in a very efficient manner.

In the accompanying drawing:

Figure 1 is a perspective view of a sage brush grubber constructed in accordance with the invention; and

Fig. 2 is a side elevation thereof.

Like numerals designate corresponding parts in both of the figures of the drawing.

By referring to the drawing it will be seen that my improved sage brush grubber is formed principally of two beams, one a main longitudinal beam 5 and the other an angular beam 6. The beam 6 may lie at any suitable angle with respect to beam 5 but it is preferably disposed at a forty-five degree angle, and it is joined to the beam 5 with a ship lap joint of such strength and rigidity as to enable the beam 6 to resist the tendency for it to swing into alignment with the beam 5 when the structure is in use.

The beam 6 carries a cutting blade 7 that extends entirely along its lower edge and is united to the beam 5 at 8. The nose of the beam 5 is indented as indicated at 9 and carries a blade 10 which extends across its lower edge. Both the blades 7 and 10 project slightly below the level of the beams 6 and 5 and the lower edges of these blades project forward to a limited extent and in such manner that the action is more of a scraping action than of a cutting action. The beam 6 carries a hook 11 which constitutes a point of attachment for a chain 12 the other end of which may be passed around the indented portion of the nose of the beam 5 and through an opening 13, this chain constituting means by which the structure may be drawn bodily along the ground.

I am well aware of the fact that it has heretofore been proposed to employ various types of V shaped structures for use as road

graders and the like, but careful consideration will show that the structure herein shown and described possesses points of novelty and advantage not possessed by any structure with which I am familiar. In the first place it is to be particularly noted that the beam 5 is of substantially the same thickness and width throughout its length and that the same is true of the beam 6. This causes the main beam to lie flat upon the surface of the ground. This main beam carries a vertical blade 14 depending from its under side adjacent its rear end and acting to hold the beam against lateral movement. The armoring of the nose of the main beam 5 by the blade 10 which extends at an angle to the line of travel of the structure and lies in substantial parallelism with the blade 7, causes the nose of the main beam to not only exercise a clearing function but keeps the nose down to the work. In other words, this inclined blade prevents lifting of the nose of the structure, that would otherwise occur.

It is to be understood that the invention is not limited to the precise construction set forth but that it includes within its purview whatever changes fairly come within either the scope or the spirit of the appended claims.

Having described my invention, what I claim is—

1. A structure of the character described comprising a longitudinally extending main beam adapted to lie and travel directly upon the ground, a beam secured thereto and extending at an angle therefrom, and blades disposed along the lower edge of the last named beam and across the nose of the main beam, the nose of the main beam lying at substantially the angle of the second named beam.

2. A structure of the character described comprising a longitudinally extending main beam, an angularly disposed beam secured thereto by a ship lap joint to thereby cause both of said beams to lie in substantially the same plane, the bottoms of both of said beams being adapted to lie directly upon and travel in contact with the ground, the front end of the main beam lying in substantial parallelism with the angularly disposed beam, a blade having its lower edge forwardly directed secured along the edge of the angularly disposed beam and extending slightly

therebelow and a blade secured upon the forward end of the main beam and conforming to the direction thereof and projecting slightly therebelow, the last named blade being forwardly inclined.

3. A structure of the character described comprising a longitudinally extending main beam, an angularly disposed beam secured thereto by a ship lap joint to thereby cause both of said beams to lie in substantially the same plane, the bottoms of both of said beams being adapted to lie directly upon and travel in contact with the ground, the front end of the main beam lying in substantial parallelism with the angularly dis-

posed beam, a blade having its lower edge forwardly directed secured along the edge of the angularly disposed beam and extending slightly therebelow and a blade secured upon the forward end of the main beam and conforming to the direction thereof and projecting slightly therebelow, the last named blade being forwardly inclined, and a blade carried by the main beam adjacent the rear end thereof and projecting therebelow in a vertical plane and lying in longitudinal alignment therewith. 20 25

In testimony whereof I affix my signature.

WILLIAM N. VANCIL
